MUFFLER FOR INTERNAL COMBUSTION ENGINE

Henry Clay Giambruno, Oakland, Calif.

Application April 28, 1955, Serial No. 504,589

3 Claims. (Cl. 60—29)

This invention relates generally to a muffler for removing CO from the exhaust gas of an internal combustion engine and has for one of its objects the provision of simple, economically made and installed means for effectively removing the CO from the exhaust gas of an internal combustion engine without reducing the efficiency of such engine.

One of the problems faced at the present time in industrial centers and also in populous congested areas, is the pollution of the atmosphere with different gases, one of the chief contributors being the internal combustion engines in automotive vehicles that discharge considerable quantities of poisonous CO, and other complete and incomplete products of combustion.

It is an object of the present invention to entrap and remove the objectionable products of combustion from the discharge gas of internal combustion engines, and at the same time to muffle the exhaust noise of such engines. This result is accomplished at no increase in back pressure in the exhaust pipe, but instead, there is an actual reduction in such back pressure as compared with that which is produced by conventional mufflers.

Other objects and advantages will appear in the description and in the drawings.

In the drawings, Fig. 1 is a part sectional and part elevational view of the invention with part of the fire wall and instrument panel of an automobile being indicated.

Fig. 2 is an enlarged sectional view taken along line 2—2 of Fig. 1.

Fig. 3 is a perspective view showing a typical installation of the invention in an automobile, the automobile being shown in dot-dash lines.

In detail, the muffler illustrated in the drawings comprises a horizontally elongated housing generally designated 1, which housing has a bottom wall 2 (Fig. 2) a top wall 3, and opposed end walls 4, 5. The housing may be substantially elliptical in cross sectional contour, as seen in Fig. 2, with the flattened sides horizontal, or it may be cylindrical or of any other suitable contour, the elliptical cross sectional contour merely conforms substantially to present practice, but it is not essential to the accomplishment of the desired results.

An exhaust pipe 7 extends from the exhaust manifold to the muffler and an end portion 8 of said exhaust manifold extends through the end wall into said muffler and terminates in a closed end 9 adjacent to the end wall 4.

Preferably, the exhaust pipe enters the muffler through end wall 5 adjacent to the upper edge of the latter, and centrally between its side edges. Then it curves downwardly at 10, after entering the muffler, and the major portion 11 that is within the muffler, extends along and adjacent to the bottom wall 2 and longitudinally of the muffler, but spaced above said bottom wall.

The lower side of the portion 11 may be provided with one row or several rows of discharge openings 12 (Fig. 2). The openings in the rows, where several are provided, after preferably in staggered relation, and the total area of these openings preferably exceeds the total cross

2

sectional area of the portion 11 by an amount sufficient to prevent any objectionable back pressure of gas in exhaust pipe 7 during operation of the engine.

A discharge pipe 15 extends at one end through the 5 end wall 4 and into the muffler, and the portion 16 of said pipe 15 that is within the muffler terminates in an open end positioned adjacent to but spaced from the end wall 5. A filter screen 17 may, if desired, be placed over the open end of portion 16.

10 This portion 16 of the exhaust pipe is preferably positioned against or substantially against the top wall 3 and may be secured to the latter by any suitable means. The pipe 15 outside the muffler 1 may extend to the rear end of the automobile (Fig. 3) in the same manner as a conventional muffler.

Inasmuch as the muffler itself, insofar as its shape and size are concerned, is comparable to a conventional muffler, and as the exhaust and discharge pipes 7, 16 are substantially the same in appearance and position as the 20 conventional exhaust and discharge pipes in an automobile, they may be secured to such vehicle in the same manner as the muffler and exhaust pipes have been secured. It is, of course, to be understood that the invention is not to be restricted insofar as use is concerned, 25 for the reason that it is adapted to be used in connection with any internal combustion engine.

If desired, a shield or baffle 20 may be positioned over 30 and secured to the portion 11 of the exhaust pipe 7. This baffle, when used, is disposed horizontally over the portion 11, but does not extend to the sides of the housing 1 (Fig. 2) thus providing passageways 21 between the edges of the baffle and the side walls of the housing for exhaust gas. This baffle may be generally of inverted U-shape so that any material that might otherwise lodge 35 on top of it will tend to slide down the same to the passageways 21.

Within the housing 1 and covering the apertured portion 11 of the exhaust pipe is a bed of loose particles of siliceous material 22. Preferably the size of these particles does not exceed approximately 30 mesh size, although they may be smaller, and the top of the bed is preferably about midway between the top and bottom walls, 2, 3 and spaced a substantial distance below the discharge pipe 16.

45 The siliceous material of this bed may be washed sand and silica gel in the ratio of from about $\frac{1}{3}$ to $\frac{1}{2}$ silica gel to $\frac{2}{3}$ to $\frac{1}{2}$ sand, by volume. The preferred ratio under normal conditions would be $\frac{1}{3}$ silica gel to $\frac{2}{3}$ washed sand.

50 In the operation of the muffler, a certain amount of water will usually be exhausted with the gas, and this water will be held in the interstices between the particles of siliceous material and will be absorbed by the silica gel.

55 It is desirous that the bed of siliceous material should be damp, but it is preferable that there should not be a bed of water in the muffler.

In order to insure adequate moisture, a source 23, of 60 water is preferably provided in the form of a receptacle secured to the fire wall and under the hood of the automobile and this carried distilled water.

A pipe 24 extends from the receptacle 23 into the exhaust pipe 7 at a point adjacent to the housing 5, and the end 25 of said pipe 24 that is within said pipe 7 is 65 directed so that its open end faces the same direction as the flow of gas in said pipe 7. A valve 26 in pipe 24 is adapted to be actuated for opening and closing the same by a control wire 27 leading to a hand control button 28 on the instrument board 29. The valve may be actuated to permit drops to be fed intermittently into the exhaust pipe for discharge of moisture into the bed

of siliceous material, or any desired flow of water can be produced.

It is desirable to remove the bed of siliceous material at relatively long intervals of time. A discharge opening is provided in the bottom of the housing 2 and thus is closed by a removable plug 30. By removing the plug and operating the engine, the siliceous material will readily be blown out of the housing through the discharge opening.

A conduit 31 extends from end wall 5 to a point under the hood of the automobile, which conduit has a removable cap 32 closing its upper end. This upper end is at a level above that of the housing 1, and the point at which the conduit opens into the housing 1 is preferably at about the desired level of the bed of siliceous material. To replenish the siliceous material the cap 32 is removed and the material is poured into the conduit 31 for passage into the housing.

In operation, it has been found that the exhaust gas from the pipe 15 is virtually free from CO when the gas is passed through the muffler, and tests conducted to determine the back pressure in the exhaust pipe 7 show less back pressure than that which exists where the conventional muffler is used. Also the present muffler is more effective in silencing the exhaust noise than with the conventional muffler.

The provision of the shield or baffle 20, in combination with the positioning of the portion 11 of the exhaust pipe adjacent to the bottom of the housing 1, effectively insures against the siliceous material uncovering the portion 11, as might otherwise occur, particularly in the case of a very abrupt stop or when the housing is tilted during the time the vehicle is climbing or descending a hill. The material quickly levels itself when the housing is anywhere near level, should the material move to any degree to one end or the other of the housing.

I claim:

1. In combination with an internal combustion engine having an exhaust manifold, a horizontally elongated housing, having a top wall, bottom wall and opposite end walls, an exhaust pipe extending from said exhaust manifold through one end of said housing to a point adjacent to the opposite end of said housing, the major portion of the pipe that is within said housing being disposed adjacent to said bottom of said housing and generally downwardly directed openings formed in said major portion of said pipe, a body of relatively small particles of loose siliceous material on said bottom wall covering said major portion of said pipe, a discharge pipe extending through the opposite end of said housing spaced above the level of said bed and extending to a point adjacent to said one end of said housing, an opening for gas formed in said discharge pipe at the end thereof that is adjacent to said one wall, a tube extending into said exhaust pipe at a point between said major portion and said engine for supplying water to be discharged into said bed, a valve in said tube for regulating the flow of water therethrough and into said exhaust pipe.

2. In combination with an internal combustion engine having an exhaust manifold, a horizontally elongated

housing, having a top wall, bottom wall and opposite end walls, an exhaust pipe extending from said exhaust manifold through one end of said housing to a point adjacent to the opposite end of said housing, the major portion of the pipe that is within said housing being disposed adjacent to said bottom of said housing and generally downwardly directed openings formed in said major portion of said pipe, a body of relatively small particles of loose siliceous material on said bottom wall covering said major portion of said pipe, a discharge pipe extending through the opposite end of said housing spaced above the level of said bed and extending to a point adjacent to said one end of said housing, an opening for gas formed in said discharge pipe at the end thereof that is adjacent to said one wall, an opening formed in said bottom wall for removal of the particles of said bed from said housing, and a removable closure closing said last mentioned opening, a filling conduit communicating with the interior of said housing through said one end wall for filling said housing with particles of siliceous material to a level disposed between said major portion of said exhaust pipe and said opening in said discharge pipe and a closure for said conduit.

3. In combination with an internal combustion engine having an exhaust manifold, a horizontally elongated housing, having a top wall, bottom wall and opposite end walls, an exhaust pipe extending from said exhaust manifold through one end of said housing to a point adjacent to the opposite end of said housing, the major portion of the pipe that is within said housing being disposed adjacent to said bottom of said housing and generally downwardly directed openings formed in said major portion of said pipe, a body of relatively small particles of loose siliceous material on said bottom wall covering said major portion of said pipe, a discharge pipe extending through the opposite end of said housing spaced above the level of said bed and extending to a point adjacent to said one end of said housing, an opening for gas formed in said discharge pipe at the end thereof that is adjacent to said one wall, an opening formed in said bottom wall for removal of the particles of said bed from said housing, and a removable closure closing said last mentioned opening, a filling conduit communicating with the interior of said housing through said one end wall for filling said housing with particles of siliceous material to a level disposed between said major portion of said exhaust pipe and said opening in said discharge pipe and a closure for said conduit, a horizontally extending baffle over said major portion of said exhaust pipe and to opposite sides of said major portion.
